Patented Nov. 13, 1923.

UNITED STATES PATENT OFFICE.

ADAM PH. QUENZER, OF BROOKLYN, NEW YORK.

CAP SPREADER.

Application filed March 31, 1922. Serial No. 548,462.

To all whom it may concern:

Be it known that I, ADAM P. QUENZER, a citizen of the United States, residing at Brooklyn, in the county of Kings and State 5 of New York, have invented new and useful Improvements in Cap Spreaders, of which the following is a specification.

This invention relates to re-shaping devices and more particularly to a device for

10 re-shaping used crimped bottle caps.

Crimped bottle caps, such as those used as bottle stoppers, are normally or ordinarily formed with a flared crimped marginal wall or skirt and a top or connecting 15 crown wall. This form of cap is first placed over the neck of the bottle to be sealed and forced tightly thereon and the crimped marginal wall contracted about the neck so that the bottle is hermetically sealed. When the 20 cap is fully applied, the crimped walls thereof are vertically disposed or substantially so. When removing the cap from its bottle, by means of the customary removing implement, the crimped walls are expanded and 25 flared outward from their normal or sealed condition and without re-shaping or restoring the cap to its original form, same is rendered unfit for further use. When once removed, these forms of caps are generally 30 thrown away.

It is an object of my invention to provide a simple, inexpensive, strong and durable device which can be readily associated with a previously used crimped cap and employed 35 to re-shape or restore the cap to its original symmetrical form, thereby permitting same to be re-adjusted and re-used as a bottle closure.

With the above and other objects in view 40 which will appear as the nature of the invention is better understood, the same consists in the improved construction and novel arrangements of parts which will herein-after be fully described, and particularly 45 pointed out in the claim.

In the accompanying drawings has been illustrated, a single and preferred form of the invention, it being, however, understood that no limitations are necessarily made to the precise structural details therein exhibited, but that changes, alterations and 50 modifications within the scope of the claim may be resorted to when desired.

In the drawings:

55 Figure 1, is a perspective view of the device.

Figure 2, is a vertical section through the die members showing same closed or in the act of re-shaping a cap.

Figure 3, is a perspective view of a 60 crimped cap showing same in its original form, and

Figure 4, is a similar view showing the shape the cap assumes when applied to a 65 bottle.

In carrying the invention into practice, I employ a pair of pivotally connected levers 5 and 6, the former carrying a jaw 7 and the latter a jaw 8. Formed as part of the jaw 7 is a female die section 9 which is adapted to 70 co-act with a male die section 10 on the jaw 8. These die sections are normally held separated with respect to each other by means of a spring 11, the latter interposed between the levers 5 and 6.

The male die section 10 is circular in plan and in vertical section, same conforms with the cross sectional form of the cap shown in Figure 3. It is provided with a circular wall 12 and a flared base wall 13. Through 80 the center of this section, a suitable finger opening 10' is formed, so that after the re-shaping operation, the finger of the operator can be extended into said opening to release the cap from the die.

The female section 9 is provided with a crown wall 14 and a short depending annular wall 15, the depth of the latter being co-extensive with the wall 12 of said male section 10.

The mating sections 9 and 10 of the die are so disposed with respect to each other and the levers 5 and 6 that they come together in parallelism when the levers are closed. Incident thereto, it will be observed that when 95 a cap of the shape shown in Figure 4 is operatively interposed between said die sections, and on bringing said sections together as described, pressure will be brought against the cap so as to force same downward until 100 the sides of the cap conform with the shape of said male section of the die. In performing this operation a used cap is quickly restored to its original form and can be again employed as a bottle stopper and contracted 105 into position around the neck of the bottle in the usual well known manner.

While I have described what I deem to be the most desirable embodiment of my invention, it is obvious that many of the details 110 may be varied without in any way departing from the spirit of my invention, and I there-

fore do not limit myself to the exact details of construction herein set forth, nor to anything less than the whole of my invention, limited only by the appended claim.

5. What I claim as new is:—

A bottle cap re-shaping device comprising a female die section, a male die section co-acting with the first said section and provided with a central opening, a pair of pivotally connected levers respectively supporting said die sections for movements toward or away from each other and formed integral

therewith, the male section having an annular vertical wall and a flared base wall, the latter merging into the former, the female 15 section including an annular wall adapted to embrace the annular wall of said male section, the depth of said annular vertical wall being co-extensive with the vertical wall of said female section.

20 In testimony whereof I have affixed my signature.

ADAM PH. QUENZER.
